UNITED STATES PATENT OFFICE.

WILLIAM S. HARBER, OF SHELDON, TEXAS.

TIE-CUTTER.

1,191,176.

Specification of Letters Patent. Patented July 18, 1916.

Application filed December 24, 1915. Serial No. 68,563.

To all whom it may concern:

Be it known that I, WILLIAM S. HARBER, a citizen of the United States, residing at Sheldon, in the county of Harris and State 5 of Texas, have invented certain new and useful Improvements in Tie-Cutters, of which the following is a specification.

This invention relates to new and useful improvements in a tie cutter.

10 The object of the invention is to provide a device of the character described designed to be used for the purpose of cutting railway ties into parts preparatory to their removal from the track after they have decayed or become worn out.

As at present removed, the spikes are first withdrawn and the discarded tie is moved endwise from under the rail and in order to accomplish this purpose it often becomes necessary to jack up the rail in order to permit the removal of the tie, and this is a difficult and laborious operation. The device herein described is used for cutting a tie in two just inside each rail and then removing the 25 same in three parts.

With the above and other objects in view the invention has particular relation to certain novel features of construction, operation and arrangement of parts, an example 80 of which is given in this specification and illustrated in the accompanying drawings wherein:—

Figure 1 shows a side elevation of the device, Fig. 2 shows a vertical sectional view 85 thereof.

Referring now more particularly to the drawings wherein like numerals of reference designate similar parts in each of the figures the numeral 1 refers to a railway 40 rail and 2 to a tie forming part of a railway track.

The numeral 3 refers to the cutter stand, whose lower end is flared to form a substantial support and which has the laterally extending fingers 4, 4 which engage under the rail while the stand is supported upon the tie. A brace 5 is slidably attached to the stand and has the depending fingers 6, 6, which embrace the tread of the rail to 45 secure the stand in vertical position. The upper end of the stand has laterally extending ears 7, 7 in parallel relation, forming between them a channel or bearing in which the cutter bar 8 slides and between these 50 ears is pivoted the socket 9 whose inner end is formed into a disk 10 said socket member

being provided to receive the handle 11. The lower end of the cutter bar carries the cutting blade 12, which in length and width is equal to or greater than the corresponding 60 dimensions, to-wit, the thickness and width of the tie to be cut, and the outer or exposed face 13 of the cutter bar is serrated, as shown in Fig. 2 forming a rack face with which the dogs 14, 14 engage. These dogs 65 are pivoted to the disk 10 on opposite sides of the axial line of the handle and are held in engagement with the teeth of said rack face by means of flat springs 15, 15 which are pivoted to the ears 7 and press against 70 said dogs. When the handle 11 is manipulated downwardly, the lower dog will engage against the alined tooth of the face 13 and force said cutter bar and the blade 12 carried thereby downwardly into the tie 75 and at the same time the other dog will be released from one tooth and will engage with the next succeeding tooth thereabove. On the upstroke of the handle the upper dog will operate to force the cutter bar and 80 blade downwardly while the other one will be released from the tooth with which it is engaged and will engage with the next succeeding tooth thereabove. Thus the cutter bar and blade are forced downwardly with 85 each stroke of the handle and said blade is thus gradually forced through the tie. In case the tie is very firm a heavy hammer or mallet may be used to strike the upper end of the bar 8 to assist in forcing the blade 90 through the tie.

What I claim is:

1. A tie cutter including a stand, laterally extending fingers carried by the lower end thereof to engage under a railway rail, a 95 slidably mounted brace carried by the stand and engaging with the tread of said rail, a cutter bar slidably mounted in said stand, whose lower end is formed into a cutting blade and means for forcing said bar 100 lengthwise relative to the stand.

2. A tie cutter including a stand, laterally extending fingers carried by the lower end thereof to engage under a railway rail, a 105 slidably mounted brace carried by the stand and engaging with the tread of said rail, a cutter bar slidably mounted in said stand, whose lower end is formed into a cutting blade, said bar also having a rack face, a handle pivoted to the stand, a pair of dogs pivoted to the handle on opposite sides of the 110 axial line thereof, which engage with said

rack face and through which the reciproca-
tion of said handle imparts a lengthwise
movement of the bar relative to the stand.

3. A device of the character described in-
cluding a stand, whose lower end is formed
into fingers which engage under the rail
of a railway track, a brace having a slideable
engagement with the stand and engaging
over the tread of said rail, a cutter bar slide-
ably mounted relative to said stand and

whose lower end is formed into a cutting
blade and means for imparting a lengthwise
movement to said bar relative to the stand.

In testimony whereof I have signed my
name to this specification in the presence 15
of two subscribing witnesses.

WILLIAM S. HARBER.
